UNITED STATES PATENT OFFICE

165,269

KITE REEL

John H. Cordell, Shreveport, La.

Application May 3, 1951, Serial No. 15,054

Term of patent 3½ years

(Cl. D34—15)

To all whom it may concern:

Be it known that I, John H. Cordell, a citizen of the United States, residing at Shreveport, in the Parish of Caddo and State of Louisiana, have invented a new, original, and ornamental Design for a Kite Reel, of which the following is a specification, reference being had to the accompanying drawing forming part thereof.

Figure 1 is a perspective view of a kite reel, showing my new design; and

Figure 2 is a top plan view thereof.

I claim:

The ornamental design for a kite reel, as shown.

JOHN H. CORDELL.
